UNITED STATES PATENT OFFICE.

WALTER SCOTT, OF PLAINFIELD, NEW JERSEY; ISABELLA SCOTT AND DAVID JOHN SCOTT EXECUTORS OF SAID WALTER SCOTT, DECEASED.

PRINTING-MACHINE.

1,232,615.

Specification of Letters Patent. Patented July 10, 1917.

Application filed December 15, 1904. Serial No. 236,933

To all whom it may concern:

Be it known that I, WALTER SCOTT, a citizen of the United States, and a resident of Plainfield, in the county of Union and State 5 of New Jersey, have invented a certain new and useful Improvement in Printing-Machines, of which the following is a specification.

The primary object of this invention is to 10 arrange a plurality of sets of printing mechanism and a plurality of folding mechanisms with their driving mechanisms so that any of them may be operated separately as independent printing and folding mechanisms, and also so that any of them may be coupled together to run at the same surface speed, whereby the webs printed by two or more of the sets of printing mechanism may be associated together and be led to a common 15 folding mechanism or mechanisms. Another object is to provide for the case where the press-room of an establishment may be too low to accommodate the usual construction of tiered machines, or which may be too 20 short to allow of placing the printing machines end to end, reference being had by the phrase "end to end" to the case where the "ends" of the machine are the places, respectively where the rolls are placed and 25 where the web or webs emerge, so that, with two such machines, placed "end to end," the webs thereof travel either toward each other, or in the same direction, and in the same vertical plane, as they go to the folding-devices. 30 35 In such case, the sets of printing-couples may have their cylinders parallel, but they are not in alinement or end to end with respect to each other. Other objects will appear hereinafter during the course of description of the specific form of the invention 40 illustrated in the drawing.

It is preferred to use what is known as "quadruple" machines, or machines having two sets of printing mechanism arranged 45 one over the other and each set of printing mechanism wide enough to accommodate a web carrying four full-sized pages abreast thereon, and to have two "quadruples" placed with their printing and impression 50 cylinders end to end, though more than two such machines may be placed with their printing and impression cylinders end to end, and each machine may have more or less than two sets of printing mechanism 55 therein without departing from the broader

aspects of the present invention. The folding-mechanisms are arranged in line with each other, with their folding and cutting cylinders, preferably at right angles to the course of the webs through the sets of printing mechanism, and means are provided whereby any web may be taken to any folder. 60

The machine illustrated in the drawing 65 may be used to produce copies containing two, four, six, eight, ten, twelve, fourteen, sixteen, eighteen, twenty, twenty-two, twenty-four, twenty-six, twenty-eight, thirty, thirty-two, thirty-four, thirty-six, forty-four, forty, forty-eight, fifty-two, fifty-six, 70 sixty, and sixty-four pages, some of them being "onset" and others being "inset."

In the practice of this invention, I arrange a plurality of sets of printing-mechanism with their printing and impression cylinders placed end to end in side by side frames, which frames may or may not be independent of each other, and provide mechanism for each frame for driving any or all of the sets of printing-mechanism 75 therein independently of printing-mechanism in any other frame, and also means whereby all of said sets of printing-mechanism may be caused to run at the same surface speed, thus allowing of the association 80 of the webs, or of cuts therefrom, and their folding and delivery as one or more products, as well as their separate delivery. In case the frames A B are not to be independent of each other, they may be formed or 85 made into one frame in any suitable manner, as by distance-pieces or otherwise. The sets of printing-mechanism, where there is more than one set to the frame, may be 90 geared together independently of the driving mechanism for that frame, and each set may be geared independently to the driving mechanism to be connected and disconnected at will independently of the other sets. There 95 may be a plurality of independent driving-mechanisms for each frame, one of which driving-mechanisms gears with certain of the sets of printing-mechanism in that frame while another driving-mechanism gears with certain other of said sets of printing-mechanism, and so on, as in Letters Patent of the 100 United States dated May 8, 1906, and numbered 819,813. Or clutches may be used to connect and disconnect the sets of printing-mechanism independently to and from a com- 105 110

mon driving mechanism for each frame, such clutch-mechanism being, for instance, of the type shown in Letters Patent of the United States dated August 19, 1902, and numbered 707,101. Also, slip-gears, or gears movable along their shafts or studs, for the purpose of moving them into and out of mesh with other gears, may be used to connect the sets of printing-mechanism in each frame with each other, whereby all sets of printing-mechanism in each frame may be driven from one or another driving-mechanism on that frame. Sets of printing-mechanism in different frames may be connected together by any suitable means to cause them to move at the same surface speed as by connecting their driving-mechanisms, though such connection may be otherwise made without departing from this invention. The webs perfected by the sets of printing-mechanism in each frame may be taken to one or more ~~four~~ adjacent to said sets of printing-mechanism, said folders being preferably in the same frame as the sets of printing-mechanism with which they ordinarily co-operate, and being preferably arranged transverse to the direction of travel of the webs through the printing-mechanism, and the folder, or pair of folders, or pairs of folders, for each frame, being in line with the folder, or pair or pairs of folders of the other frame or frames, whereby all the webs from all the sets of printing-mechanism may be associated or imposed one on another and be taken to the same folding-mechanism or mechanisms. The folders may be of any type or construction appropriate to the kind of folding required, and may be driven in any suitable or known manner, either from driving-mechanism for the sets of printing-mechanism or from any set of printing-mechanism, and slip-gears may be provided for silencing any folder not in use. And it is noted that arrangements may be made, by suitable gearing, for using any folder in connection with any set or sets of printing-mechanism. The printing-mechanism may be arranged to print two or more pages abreast on each web, and the column-rules may run around or lengthwise of the form or plate cylinders, appropriate folding mechanism being provided; or the sheets may be delivered flat or unfolded. Suitable paste-applying devices may be provided for applying lines of paste lengthwise of and also transversely of the webs, as in Letters Patent of the United States dated March 3, 1903, and numbered 721,840. Where sheets or cuts are collected or imposed, transverse lines of paste may be applied to them, so that the completed product will be pasted together; thus, if a folder of the type shown in Letters Patent of the United States dated July 3, 1900, and numbered 652,817, be employed, which folder also collects sheets or

cuts, a paste-blade of the type shown in Letters Patent of the United States dated May 29, 1877, and numbered 191,494, may be used in conjunction with the cylinder marked 7 in said Patent 652,817, to apply paste to the sheets being carried around thereby.

One embodiment of the invention is illustrated in the accompanying drawing, forming part hereof, in which

Figure 1 is a side-elevation, with parts omitted; Fig. 2 is a plan; and Fig. 3 is a view, from the right in Fig. 1, with parts broken away.

In the drawing, the reference letters A B mark independent frameworks, in each of which two sets, *a* *b*, of printing-mechanism are mounted with their cylinders parallel, and the cylinders of each set being geared together as usual. Beneath the frame A is a driving shaft *c* and beneath the frame B is a driving-shaft *d*, said shafts *c* *d* being in line with each other and having belt-pulleys *e* thereon by means of which they may be driven from electric motors or otherwise. The reference *f* marks bevel gearing for connecting the shafts *c* *d* with upright shafts *g* at the sides of the frames A B, and *h* denotes bevel gears splined to, or otherwise arranged to cause them to rotate with their shafts and slideable along said shafts into and out of mesh with bevel gears *h* fast on shafts of the sets *a* of the printing mechanism, said gears *h* being held in place by any suitable means, as by set-bolts *i*.

The printing-cylinders in frame A are aligned with the like cylinders in frame B, and the like is true of the impression cylinders in the said frames.

The shafts *c* *d* may be connected to and be disconnected from each other in any suitable manner, as by a clutch *k*, one member at least of which is slideable along its shaft to cause it to engage with and to disengage it from the other clutch-member, as by a spline *m* and set-bolt *n*.

The reference *o* denotes guide rolls for the webs and the reference *p* denotes disks for applying lines of paste lengthwise of the webs, there being rollers *q* to coact with the disks *p*. The reference *r* marks angle-bars for changing the course of the webs from the vertical plane in which they move in passing through the sets of printing-mechanism to the plane in which they move in passing to and through the folding mechanisms, it being preferred that there be no more such changes than are indicated in the machine illustrated in the drawing, and *s* denotes slitters for splitting the webs lengthwise. It is obvious that the usual adjustable register rolls may be used (not shown).

In the instance shown, a known form of folder is illustrated, the folders comprising rollers *t*, triangles *u*, rolls *v*, and nipping or

fold-laying rolls w , to which are added cutting, folding, and delivery mechanisms comprising cutting and folding-cylinders x y , folding rolls z , and delivery devices consisting essentially of the well-known S-fly S and delivery tapes T. The cylinders x y shown in the drawing are of the type illustrated in Letters Patent of the United States dated December 1, 1896, and numbered 5 572,280, with the addition thereto of cutting blades and grooves as in Letters Patent of the United States numbered 721,840 and dated March 3, 1903. Since these cylinders x y are shown in detail in said 10 Patent 572,280, and since they may be replaced by the cylinders shown in Patent 721,840, or by any other suitable form of collecting and folding mechanism and cutting mechanism either forming part of or independent 15 of the collecting and folding mechanism, the details of these cylinders x y are not herein illustrated. The rolls t v w , and cylinders x y may be driven in any suitable or known manner, either from the driving 20 mechanisms proper or from and in combination with any set of printing-mechanism, and may be arranged to be silenced when not in use. For purposes of illustration merely, I show bevel and other gearing 2, 3 for connecting said parts with the shafts c d , and it is remarked that any of these gears may be slip-gears.

Instead of the longitudinal folders shown herein, which are suited to the case where the 35 column-rules run around the form cylinders, folders of the type illustrated in Letters Patent of the United States dated October 31, 1893, and numbered 507,758, may be employed to meet the case where the column-rules run along or lengthwise of the form 40 cylinders. Cross association can be had in each case, as indicated by the lines 4, whereon the arrows indicate the direction of motion of the webs. For the purpose of sustaining the webs in cross-association, guide 45 rolls may be provided. Where folders of the type last-mentioned above are employed, their cylinders are placed parallel to the rolls t , as will be understood, whether or not 50 these last be at right angles to the cylinders of the printing mechanism, the only essential in this respect being that cross-association shall be had.

By the use of long and short angle-bars r 55 and by placing them on different levels, as shown in Fig. 1, all sections of each web may be directed to one particular folder, and all webs may be directed to one particular folder, also.

60 The subject-matter of my pending application, Serial Number 498,083, is not herein claimed.

What I claim as new and desire to secure by Letters Patent of the United States is—

65 1. The combination of a plurality of sets

of printing mechanism arranged in side by side frames, driving mechanism for each frame for driving printing mechanism therein independently of printing mechanism in any other frame, and folding mechanisms arranged at the ends of the sets of printing mechanism with their longitudinal axes in line with each other, with means for guiding the webs from the printing mechanism to said folding mechanisms, and 70 means whereby said sets of printing mechanism may all be caused to run at the same 75 surface speed.

2. The combination with a plurality of sets of printing mechanism arranged in side 80 by side frames, driving mechanism for each frame for driving printing mechanism thereof independently of printing mechanism in any other frame, longitudinal folders arranged at the ends of the sets of printing 85 mechanism with their longitudinal axes in line with each other, means for guiding the webs from said sets of printing mechanism to said folders, and means whereby said sets of printing mechanism may be 90 caused to run all at the same surface speed.

3. The combination with a plurality of double width sets of printing mechanism arranged in side by side frames, driving mechanism for each frame for driving printing mechanism therein independently of printing mechanism in the remainder of said frames, and folding mechanisms arranged at the ends of the sets of printing 95 mechanism with their longitudinal axes in 100 pairs in line with each other, of means for guiding the webs from said sets of printing mechanism to said folding mechanisms, and means whereby said sets of printing mechanism may all be caused to run at the 105 same surface speed.

4. The combination with a plurality of double-width sets of printing mechanism arranged in side by side frames, driving mechanism for each frame for driving 110 printing mechanism therein independently of printing mechanism in the remainder of the frames, and longitudinal folders arranged at the ends of the sets of printing mechanism in pairs with their longitudinal axes in line with each other transversely of the said frame, of means for guiding the webs from said printing mechanism to said folders, and means whereby said sets of printing mechanism may be caused all 120 to run at the same surface speed.

5. The combination of a plurality of frames arranged side by side, a plurality of sets of printing mechanism in each frame, driving mechanism for each frame for driving printing mechanism therein independently of printing mechanism in the remainder of the frames, means for connecting and disconnecting each set of printing mechanism to and from its driving mechanism, 125 130

means whereby said sets of printing mechanism may be caused to run all at the same surface speed, folding mechanisms arranged at the ends of the sets of printing mechanism 6 with their longitudinal axes in line with each other, and means for guiding the webs from said printing mechanism to said folders.

6. The combination of a plurality of 10 frames arranged side by side, a plurality of sets of printing mechanism in each frame, driving mechanism for each frame for driving printing mechanism therein independently of printing mechanism in the remainder of the frames, folding mechanisms arranged at the ends of the sets of printing mechanism with their longitudinal axes in line with each other, means for guiding the webs from said sets of printing mechanism to said folders, means for causing said sets of printing mechanisms to run all at the same surface speed, and means for silencing parts not in use.

7. The combination of a plurality of side 25 by side frames, a set of printing mechanism for and in each frame, independent driving mechanisms for said sets of printing mechanism, a plurality of folding mechanisms arranged in line with each other at the ends 30 of the printing mechanism, means whereby the webs may all be taken to any of said folders, means whereby the sets of printing mechanism in use may all be caused to run at the same surface speed, and means where- 35 by parts not in use may be silenced.

8. The combination of a plurality of side by side frames, a set of printing mechanism for and mounted in each frame, a driving mechanism for each frame for driving the 40 set of printing mechanism therein independently of the sets in the remainder of the frames, a plurality of folders arranged in line with each other at the ends of the printing mechanism, means whereby the 45 webs may be taken to any of said folders, and means for coupling together said driving mechanisms.

9. The combination of two printing and 50 folding machines in side-by-side frames, with the folders arranged with their longitudinal axes in line with each other at the ends of the printing mechanism, means for driving said machines independently of one another, and means for causing them to 55 move in unison or at the same surface speed.

10. The combination of two double-width 60 printing machines arranged in separate frames placed side by side, each machine feeding from one or more rolls of paper and each having two longitudinal formers or folders arranged side by side at right angles to the printing machines and the folders for the two machines being in line with each other at the ends of the printing mechanism 65 and means for changing the course of the

webs from the course they take in going through the printing machines to the course they take in going through the folding machines, whereby without additional turners or angle bars and without again changing the course of the webs, all webs may be superposed over one another, whether the machines operate as independent presses, or are driven at the same surface speed and operated as one machine.

11. The combination of two multi-roll 75 double width printing machines arranged in separate frames side by side, each having two longitudinal side by side folders arranged with the cutting and folding cylinders parallel to the cylinders of the printing machines, said folders for one machine being in line with those for the other at the ends of the printing mechanism, with means for bringing all the webs into line, whereby 80 the webs may be superposed without changing the direction of their travel after being brought into line, with means for coupling together and uncoupling said printing machines.

12. The combination of two multi-roll 90 printing machines in side by side frames, each having two longitudinal side by side folders at right angles to the printing machines and in line with each other at the 95 ends of the printing mechanism, and means for changing the direction of travel of the webs from the course taken in going through the printing machines to the course to be taken in going through the folding machines, whereby the same means which change the travel of the webs may cause all the webs to be superposed, whether the machines are operated independently or are coupled together and operated as one machine.

13. The combination of a plurality of 100 printing machines placed in side by side frames with their folding mechanisms set at right angles to the printing mechanisms 110 with their longitudinal axes in line with each other at the ends of the printing mechanism, and means for driving each printing machine independently, with means for causing all said machines to run at the same surface speed and to operate as one machine.

14. The combination of independent parallel frames, sets of printing mechanism mounted in each of said frames, driving mechanism for each frame for driving printing mechanism therein independently of printing mechanism in any other frame, folding mechanisms arranged with their longitudinal axes in line with each other at the delivery ends of said sets of printing 125 mechanism, and means whereby said sets of printing mechanism may be coupled together to run at the same surface speed and may be uncoupled to run independently.

15. In an apparatus for printing and fold- 130

ing papers, the combination of a first printing mechanism adapted to perfect a continuously moving web; a first slitter in line with and adapted to slit the web perfected by
5 said first printing mechanism; a second printing mechanism end-to-end with respect to said first printing mechanism and adapted to perfect a second continuously moving web; a second slitter in line with and
10 adapted to slit said second perfected web; a pair of turners in line with and beyond said first printing mechanism as the web runs, and adapted to effect a single quarter-turn of the members of said first web to run
15 in single alinement toward a common center between the pairs of turners; another pair of turners beyond and in line with the second printing mechanism as the web runs, and in range with said first named pair of
20 turners and adapted to effect a single quarter-turn of the members of said second web,

to cause them to run in single alinement toward a common center between the pairs of turners and in line with the quarter-turned web-members running from said first named 25 pair of turners; first-folder means adapted to make the first-fold of quarter-turned and alined web-members running from both pairs of turners; second-folder mechanism adapted to make the second-fold of papers 30 first-folded by said first-folder means; and a delivery device adapted to deliver the second-folded papers running in a line parallel to the initial line of travel of one of the webs.

Signed at New York city in the county of New York and State of New York this 26th day of October, A. D. 1904.

WALTER SCOTT.
